PROGRESSIVE ILLUMINATING MEANS

Richard H. Seaman, Los Angeles, Calif., assignor
to Mega Corporation, Los Angeles, Calif., a
corporation of California

Application May 24, 1947, Serial No. 750,352

7 Claims. (Cl. 315—315)

1

The present invention relates to improvements in progressive illuminating means.

More particularly, the present invention relates to control means for one or a plurality of fluorescent tubes whereby the various portions of each or all of said tubes may be activated progressively according to a predetermined program. Such devices are useful for advertising and other purposes.

An object of the present invention is to provide progressive illuminating means involving one or more fluorescent tubes which illuminating means involve only simple and sturdy parts which are not likely to get out of order.

A further object is to provide progressive illuminating means involving one or more fluorescent tubes, each of which tubes includes a cathode and a plurality of anodes spaced therealong together with means for progressively completing circuit through said anodes to provide a progressive illumination.

A further object is to provide an improved progressive illuminating means made up of simple and sturdy parts and which is well adapted to meet the needs of commercial service.

Further objects will appear as the description proceeds.

The one sheet of drawing illustrates diagrammatically a preferred embodiment of the present invention.

The numerals 10—10 indicate fluorescent tubes, each of which is provided with a cathode 11 and a plurality of anodes 12, 13, 14 and 15. Said tubes are preferably of the hot cathode type. The number of anodes may be chosen within a relatively wide range, the number and the spacing of the anodes depending upon the type of service in which the device is to be used. Any number of tubes may be used.

The numerals 16 and 17 indicate a supply circuit which may be connected to a source of alternating current. The circuit 16, 17 is provided with the fuse 18 and the main switch 19. The circuit 16, 17 supplies the primary 20 of a transformer 21 and also supplies the primary 22 of the high reactance transformer 23. The transformer 23 is provided with the secondary winding 25, the two terminals thereof being connected to the plates of the tubes 26—26 of the full wave rectifier assembly or uni-directional power source 27. The transformer 21 is utilized for heating the cathodes 11—11 of the tubes 10—10 and the cathodes of the tubes 26—26 and for this purpose is provided with the plurality of secondary windings 28—28 connected to the

2

corresponding cathodes in the tubes 10—10 and with the secondary winding 29 connected to the cathodes of the rectifying tubes 26—26. The mid-point of the secondary winding 25 is adapted to be connected by means of the conductor 30 to the cathode 11 of the first tube 10. The last anode, 15, of the first tube 10 is connected to the cathode 12 of the next tube 10 by means of the conductor 31. The conductor 30 has interposed therein the time-delay switch 31a. This switch may be of either the thermal or magnetic type and is illustrated as being operable in response to a coil 31b connected across the terminals of the primary 22 of the transformer 23. The time-delay switch 31a will provide a delay in the operation of the uni-directional power source until the cathodes have been heated.

The numerals 32, 33, 34 and 35 indicate relays adapted to complete circuit successively to the anodes, 12, 13, 14 and 15 of the first tube 10. The numerals 36, 37 and 38 indicate relays adapted to complete circuit successively to the anodes 12, 13, 14 and 15 of the second tube 10. The relays 32, 33, 34, 35, 36, 37 and 38 may be of known types readily purchasable in the market and need not be described in detail herein. It will be sufficient to state that each of said relays is of the time-delay type and will operate only after the lapse of a predetermined interval (which should preferably be variable at the will of the operator) after being energized.

The relays 32, 33, 34, 35, 36, 37 and 38 may be of similar construction, each being provided with a core 39 and operating coil 40, a two-position switch arm 41 and a pair of relatively stationary contacts 42 and 43. One terminal of the coil 40 of the relay 32 is connected to the positive side of the uni-directional power source 21 and the other terminal of said coil is connected to the switch arm 41 of that relay. Each of the stationary contacts 42—42 of the various relays is connected to its individual anode 12, 13 or 14 of the tubes 10—10. The stationary contact 43 of the relay 32 is connected to one terminal of the operating coil 40 of the next relay, 33. The other terminal of the operating coil of the relay 33 is connected to the switch arm 41 of that relay. The relatively stationary contacts 43—43 of the relays 33 and 34 are connected to the operating coils of the next succeeding relays, respectively. The stationary contacts 43 of the relay 35 is connected to one terminal of the operating coil on the relay 36 associated with the second tube 10. The other terminal of this operating coil is connected to the switch arm

41 of said relay 36. The stationary contacts 43-43 of the relays 36 and 37 are connected to the switch arm 41 of the relays 36 and 37, respectively. The relatively stationary contact 43 of the relay 38 is connected to the anode 15 of the last of the tubes 10 through a conductor 44.

Interposed in the conductor 44 is a relay 45 which may be a relay of the thermal type or other delayed-action type which will have the function of extinguishing the illumination of the tubes 10-10 after the lapse of a predetermined time interval following the completion of the illumination of said tubes.

The drawing illustrates schematically a type of relay 45 which may be employed in connection with the conductor 44. Said relay includes a switch 46 biased to closed position located in the circuit connecting the rectifier assembly 27 with the operating coil 40 of the relay 32. Located in the conductor 44 is the operating coil 47 adapted after the lapse of a predetermined time interval (which should be variable at the choice of the operator) to open the switch 46. The opening of the switch 46 will break the circuit through both tubes 10-10, the switch 46 will return to its biased closed position and the progressive illumination of the tubes 10-10 will start anew.

A preferred mode of operation of the above described embodiment of the present invention is substantially as follows:

With the main switch 19 open, none of the operating coils of the relays 32, 33, 34, 35, 36, 37 and 38 will be energized and each of the switch arms 41 of said relays will be in its biased position so that said switch areas will engage the contacts 42-42 which contacts are electrically connected to the anodes of the tubes 10-10. Upon closure of the main switch 19 the transformer 21 will be energized whereby the secondary windings 28, 29 thereof will deliver heating current to the cathodes 11-11 of the tubes 10-10 and 26-26. After the lapse of a predetermined time interval, the time-delay switch 31a will close and full wave impulses will be delivered from the positive side of the uni-directional power source 27 through the coil 40 of the relay 32, switch arm 41 and contact 42 to the anode 12 of the first tube 10. Discharge will occur between the anode 12 and the cathode 11, the current returning through the conductor 30 and switch 31a to the midpoint of the secondary winding 28 of the high reactance transformer 23. That portion of the first tube 10 between the anode 12 and the cathode 11 will be illuminated.

After the lapse of a predetermined period of time after the energization of the coil 40 of the relay 32, said relay 32 will draw the switch arm 41 into engagement with the contact 43 of the relay 32, thereby completing circuit from the rectifier assembly through the coil 40, switch arm 41, and contact 43 of the relay 32 to the coil 40 of the relay 33 through the switch arm of said relay to the anode 13 of the tube 10. Discharge will occur in the first tube 10 between the anode 13 and the cathode 11 thereof, current returning through the conductor 30 to the midpoint of the secondary winding 28 of the transformer 23. After the lapse of a predetermined time interval (which should be variable at the will of the operator) said relay 33 will operate to complete circuit to the next succeeding anode, resulting in the progressive ionization of the first tube 10. The relays will be energized in succession. When

relay 35 has been energized and has moved its switch arm 41 into engagement with its contact 43, circuit will be completed through the operating coils of the relays 32, 33, 34, 35 and 36 to the anode 12 of the second tube, whence circuit may be traced to the cathode 11 of the second tube through the conductor 31, through the first tube 10, through the conductor 30 to the negative side of the rectifier assembly 27. The relays associated with the second tube 10 will be energized in succession, completing circuit through the time-delay relay 45 to the anode 15 of the last tube 10 and from tube to tube back through the conductor 30 to the rectifier assembly 27. After the lapse of a predetermined time interval, the relay 45 will become operative to break circuit between uni-directional power source 27 and the tubes 10-10, discontinuing the illumination of said tubes and allowing each of the relays to return to biased position wherein the switch arms 41 thereof engage their respective contacts 42. After the lapse of a predetermined time interval determined by the setting of the relay 32, the tubes 10-10 will go through another cycle of progressive illumination, these cycles being repeated until the main switch 19 is opened.

Though a preferred embodiment of the present invention has been described in detail, many modifications will occur to those skilled in the art. It is intended to cover all such modifications that fall within the scope of the appended claims.

What is claimed is:

1. In progressive illuminating means, a gaseous tube of the hot cathode type having a cathode and a plurality of anodes, each of said anodes having connected thereto a time-responsive relay, each of said relays having a switch contact biased toward electrical connection with its individual anode and adapted after a lapse of a predetermined time interval to pass current to the next succeeding anode in said tube.

2. In progressive illumination means, in combination, a gaseous tube of the hot cathode type having a cathode and a plurality of spaced anodes, each of said anodes having a relay connected thereto, each of said relays including a switch member normally connecting it with its corresponding anode and adapted alternatively to be connected through the next succeeding relay to the anode associated with said next succeeding relay.

3. In combination, a plurality of gaseous tubes, each provided with a cathode and each provided with a plurality of anodes, said tubes being connected in series, a plurality of relays associated with said anodes, each of said relays being normally biased to a position in which the operating coil thereof is in electrical connection with its corresponding anode but adapted upon energization to have electrical contact through the operating coil of the next succeeding relay to the anode associated with said next succeeding relay.

4. In combination, a plurality of gaseous tubes, each provided with a cathode and each provided with a plurality of anodes, said tubes being connected in series, a plurality of relays associated with said anodes, each of said relays being normally biased to a position in which the operating coil thereof is in electrical connection with its corresponding anode but adapted upon energization to have electrical contact through the operating coil of the next succeeding relay to the

anode associated with said next succeeding relay, and time-responsive circuit control means for interrupting circuit through said tubes.

5. In progressive illuminating means, a gaseous tube having a cathode and a plurality of anodes, a plurality of time-responsive relays, each having an operating coil, a movable switch element and a pair of contacts, each of said anodes being directly connected to a corresponding contact of said pairs of contacts, the other of said contacts being connected through the operating coil of the next succeeding relay to the movable switch element of said next succeeding relay.

6. In progressive illuminating means, a plurality of gaseous tubes, each having a cathode and a plurality of anodes, said tubes being connected in series, a plurality of time-responsive relays, each having an operating coil, a movable element and a pair of contacts, one of the contacts of each relay being electrically connected to a corresponding anode in said tubes, each of said relays being adapted upon energization to complete a circuit from the operating coil thereof, the movable switch element thereof through the operating coil and the movable switch element of the next succeeding relay to the next succeeding anode.

7. In progressive illuminating means, a plu-

rality of gaseous tubes, each having a cathode and a plurality of anodes, said tubes being connected in series, a plurality of time-responsive relays, each having an operating coil, a movable element and a pair of contacts, one of the contacts of each relay being electrically connected to a corresponding anode in said tubes, each of said relays being adapted upon energization to complete a circuit from the operating coil thereof, the movable switch element thereof through the operating coil and the movable switch element of the next succeeding relay to the next succeeding anode, and means responsive to the flow of current to the last of said anodes for interrupting the flow of current through said tubes.
